UNITED STATES PATENT OFFICE.

JAMES N. WEIKLY, OF JERSEY CITY, NEW JERSEY.

FLUID-PRESSURE SYSTEM.

1,300,529.

Specification of Letters Patent. Patented Apr. 15, 1919.

Application filed March 18, 1918. Serial No. 223,082.

To all whom it may concern:

Be it known that I, JAMES N. WEIKLY, a citizen of the United States, and a resident of Jersey City, in the county of Hudson and State of New Jersey, have invented certain new and useful Improvements in Fluid-Pressure Systems, of which the following is a specification.

The invention relates more particularly to 10 the compressed air systems employed for applying the brakes of railway cars, and said invention is directed to the production of certain novel valves and coöperating mechanisms carried thereby to be used as substitutes for the usual angle valves or cocks employed on the train pipes at each end of each car and which angle cocks receive the coupling hose members which connect the train pipe of one car with that of the next adjacent car.

The object of my invention is to provide a novel angle cock or valve contributing by its peculiarities of operation and capabilities of use, very greatly to the safety of a train of 25 cars.

The angle cock or valve of my invention comprises a main inclosing casing to be connected with the train pipe and coupling hose member as usual, a rotary plug for opening 30 and closing the main passage through said casing, an auxiliary casing which is at one side of and preferably integral with said main casing and which affords two valve-chambers, valves in said chambers, independent ports controlled by said valves and leading from said chambers to the open air, and independent passages controlled by the main plug and leading respectively from the 35 hose side of the main casing to one of said chambers and from the train side of the said main casing to the other of said chambers and which passages are both closed by said main plug when it is in its open position and are both opened when said plug is in its 40 closed position. The angle-cock or valve possesses features of construction other than those just enumerated, and all of its details will be understood from the description hereinafter presented.

50 When the main plug is turned to its closed position and thereby opens said passages communicating with said valve chambers, the air in the hose will flow into one of said chambers and effect the movement of the 55 valves in both chambers to uncover the outlet ports from said chambers, with the result

that the air in the hose will exhaust through one of said ports and the air in the train pipe will exhaust to some extent through the other of said ports, and that when the air in the hose has exhausted sufficiently the pressure of air in the train pipe will reseat said valves to move them to closed positions, thus closing the end of the train pipe.

Each angle valve may serve as an emergency brake to be operated by a trainman at either end of any car of a train for applying the brakes and stopping the train.

When it is desired to uncouple a car from a train, the angle valves at the forward end of that car and the rear end of the adjacent car ahead will both be closed, thereby, in accordance with my invention, permitting the air in the coupling hose members to exhaust and the air in the train pipes to sufficiently exhaust to apply the brakes; and under this condition the engineer can restore the pressure in the train pipe line ahead of the car to be left behind and move the train on from said car, the connecting hose members of said car and the car ahead being pulled apart or uncoupled without manual attention and the uncoupled car being left with its brakes applied and the end of its air-pipe tightly closed by the pressure of the air in said pipe. My invention obviates the very great danger of uncoupling the air-hose when the same is under pressure and does so by permitting the pressure to exhaust before the hose is uncoupled, and my invention also and in the same way obviates the great expense incident to the damage to the pure rubber gaskets when the air-hose is uncoupled while under pressure.

My invention is advantageous in many ways, and will be fully understood from the detailed description hereinafter presented, reference being had to the accompanying drawings, in which:

Figure 1 is a side elevation of adjacent 10 portions of two train air-pipes equipped with the angle-cocks or valves of my invention and shown as coupled together by the usual air-hose members;

Fig. 2 is a central vertical longitudinal 10 section through the angle-cock or valve of my invention, the same being shown as in its normal open operative position, and the section being on the dotted line 2-2 of Fig. 4;

Fig. 3 is a vertical transverse section 11 through the same taken on the dotted line 3-3 of Fig. 4;

Fig. 4 is a top view of the same;

Fig. 5 is a central vertical longitudinal section through the same and showing the main plug as having been turned to closed 5 position;

Fig. 6 is a horizontal section through the same taken on the dotted line 6—6 of Fig. 2;

Fig. 7 is a horizontal section through the same taken on the dotted line 7—7 of Fig. 2, 10 and

Fig. 8 is a section through the same taken on the dotted line 8—8 of Fig. 2.

In the drawings, 10 designates portions of two adjacent train air-pipes, 11 the angle 15 valves of my invention applied on the adjacent ends of said pipes and 12 the usual air-hose members coupling said pipes together.

Each car has at each end of its train pipe 10 one of the valve 11, and Fig. 1 is 20 presented to indicate sufficient of the mechanism of two adjoining cars.

The angle-valve comprises a main cast metal casing 13 adapted at its end 14 to be connected with the pipe 10, as usual, and 25 at its end 15 to receive the hose member 12 in the customary manner.

The casing 13 has the customary through passageway 16, and said casing incloses and affords a suitable seat for the tapered plug 30 or main valve 17, which has the customary opening or port 18 to stand in line with the passageway 16 when the plug is in its open position, shown in Figs. 2 and 3, and suitable side surfaces to close said passageway 35 when the plug is turned to its closed position shown in Fig. 5. The plug 17 may be held in place by a threaded cap 19 or in any other suitable way, and the casing 13 preferably contains a bearing sleeve or bushing 20 for said plug and which is stationary with and may be considered as a part of the casing.

Upon the upper end of the plug or main valve 17 is formed a polygonal head 21 to receive the usual well known angle-cock operating-handle 22 or other suitable operating means, and on the casing 13 adjacent to said head 21 are the usual stop-lugs 23, 24 (Fig. 4) to coöperate with said handle 45 in stopping and locking said handle in its two positions in the customary known manner, the lug 23 serving as the stop when the handle is moved to turn the plug 17 to open position, and the lug 24 serving as the stop 50 when said handle is moved to turn said plug to closed position.

The new features more particularly related to my invention will now be described, and I may first refer to the auxiliary casing 60 25, which for convenience, compactness and saving of expense I cast on the side of the main casing 13.

The casing 25 contains in its end portions two valve chambers 26, 27, respectively, and 65 the outer ends of these chambers are closed

by plugs 28, 29. The chambers 26, 27 at their inner ends are separated from each other by a partition 30 which has an outlet port 31 leading from the chamber 27. The partition 30 has a vertical hole 32 to receive 70 and guide a valve stem 33 on whose lower end is secured a valve 34, preferably of the piston type, adapted to the chamber 26 and when in its lower position to close an outlet port 35 leading from said chamber and when elevated to open or uncover said port. 75

The partition 30 contains a vertical opening 36 which is in communication with the outlet port 31, and around the upper edges of said opening 36 is formed a valve seat for 80 the valve 37 confined within the chamber 27. The valve 37 has a depending fluted stem which guides in the opening or hole 36 and may engage the flat top of the stem 33 of the valve 34. The valve 37 has an upwardly 85 extending stem 38 which guides within a thimble 39 depending from the plug 29, as shown in Fig. 3. In the practical operation of the mechanism the valve 34 ascends to uncover the port 35 and through the stem 90 33 pushes the valve 38 to open position, the upward movement of said valves being caused by the air pressure in the hose connections, and thereafter due to the pressure in the train-pipe acting on the valve 37, 95 said valve 37 is forced downwardly to its seat and acting against the stem 33 forces the valve 34 downwardly to cover the port 35.

In the hose-end of the main casing 13 100 there is formed a passage or duct 40 leading to a segmental groove 41 formed in the lower side portion of the main plug or valve 17, as clearly illustrated in Figs. 2 and 8, there being no outlet from the segmental groove 41 when the angle-valve is in its open position, shown in Figs. 2 and 8. About in line with the plane of the segmental groove 41 a duct 42 is formed in the valve casing and leads to the chamber 26 of 110 the auxiliary valve casing 25 and terminates below the valve 34 in said chamber. In the normal operative position of the angle valve, the inner end of the duct 42 is closed by the external surface of the valve or plug 17, 115 as shown in Fig. 8, and at such time there is no communication between the hose-end of the main valve casing and the chamber 26 of the auxiliary casing 25. When, however, the valve or plug 17 is turned to closed 120 position, shown in Fig. 5, the segmental groove 41 will be carried into communication with the duct 42 and will also remain in communication with the passage or duct 40, and under such condition the air in the 125 hose 12 may exhaust through the duct 40, segmental groove 41 and duct 42 and act against the lower end of the valve 34 to elevate said valve and through said valve effect the upward movement of the valve 37 130.

from its seat. When the valve 34 is moved upwardly by the air pressure in the hose 12, it uncovers the port 35, so that said air may exhaust through said port 35.

5 In its upper side portion the valve or plug 17 is formed with a segmental groove 43, and the valve casing 13 in the train end of said casing is formed with a duct 44 which in the open position of the angle-valve is 10 held sealed by the plug 17, as shown in Fig. 7. When the plug 17 is turned to closed position, shown in Fig. 5, its segmental groove 43 will be carried to a position to connect the duct 44 with a duct 45 leading into the 15 chamber 27 of the auxiliary casing 25, and under this condition it may readily be seen that the air pressure in the train pipe may exhaust to some extent through the duct 44 into the segmental groove 43 and thence 20 through the duct 45 into the valve chamber 27 at the upper side of the valve 37 therein. In the practical operation of the mechanism when the plug 17 is turned to closed position, the air in the hose will exhaust, as 25 hereinbefore described, through the passage 40, segmental groove 41 and duct 42 into the valve chamber 26 and effect the elevation of both valves 34, 37, and thereupon after the exhaust in the hose connections becomes 30 sufficient and the pressure of the air therein is overcome by the pressure in the train pipe, the train pipe pressure acting on the valve 37 will seat said valve and through the same and the valve stem 33 move the valve 34 to 35 closed position. An important feature of this operation is that the air in the train-pipe exhausts through the angle-valve to a sufficient extent to apply the brakes and that the end of the train-pipe at which the angle- 40 valve is located becomes sealed by the air pressure acting against the valve 37, thus leaving the end of the pipe so sealed that it may retain the compressed air. A further important feature of the operation is that 45 after the air has exhausted from the hose, the train may be moved ahead from a car to be uncoupled and the two members of the hose merely pulled apart without manual attention. When a car is to be uncoupled 50 from a train, the forward angle-valve of that car and the rear angle-valve of the next adjacent car ahead will both be turned to closed position, thereby permitting the hose members to exhaust and the train pipes to sufficiently exhaust to apply the brakes. Thereafter the engineer may, with the use 55 of his pump, restore the pressure in the train-pipe line ahead of the car to be uncoupled and move the train ahead, separating the two members of the hose and leaving the uncoupled car stationary on the tracks with its brakes set. The turning of any one angle-valve from open to closed position will result in the air exhausting at 60 both sides thereof and in the brakes being

applied, but whenever a car is to be uncoupled, the two adjacent angle-valves should be turned to closed position, so that when the train moves ahead from the car to be left, the then rear angle-valve of the train 70 will be sealed by the closing of the valve 37.

A further feature of my construction is that I provide a warning for compelling a full movement of the handles 22 and plug 17 to their open position, or that shown in 75 Fig. 2, and these means comprise a duct 46 formed in the upper portion of the hose-end of the valve casing, a segmental groove 47 formed in the upper side portion of the plug 17 and a very small escape port 48 formed in the casing 13 above said duct 46 and in position to communicate with the groove 47 and duct 46 at anytime at which the plug 17 has not been fully turned to its proper open position. In any instances in 80 which the plug 17 has not been turned to its fully open position, the air in the hose connections will exhaust through the duct 46 into the groove 47 and issue from the duct 48 with a sound which will attract the 85 attention of the trainman and warn him that he has not properly operated the valve and must move the plug 17 to its full open position. The air issuing from the small duct 48 has a whistling sound after the 90 nature of escaping steam, and a trainman will thereby be warned to open the valve fully.

The manner of utilizing my invention in uncoupling cars will be fully understood without further explanation, and it will be 100 obvious that a trainman at either end of any car of the train may, by operating one of the handles 22, apply the brakes. A further important utility of my invention is that it may be utilized, for instance on long freight 105 trains, for permitting a trainman at any part of the train to send in a signal to the engineer. An annunciator may be provided in the cab and a trainman at any portion of a long freight train could effect the 110 operation of said annunciator, according to such code of signals as might be adopted by oscillating one of the handles 22 quickly back and forth so as to operate the annunciator by the reduction of pressure in the 115 train pipe-line.

My invention is not limited to what may be technically called an angle-cock or valve, since so far as the invention is concerned it makes no difference whether the hose-end of 120 the valve casing inclines downwardly at an angle, such outline for the hose-end of the casing being for the benefit of the hose, so that it may sag downwardly in a proper manner, and having nothing whatever to do with the operation of the novel features constituting my invention. The words "angle valve" or "angle cock" as used in this application are not to be considered as words of limitation, but as generic expressions in- 125 130

dicating the valves at the ends of train-pipes adapted to receive the hose-members. My invention is not limited to the angular formation of the valve casing, nor in every instance to the use of the valve at the ends of the train-pipes, since this valve is of novel construction and operation and if interposed anywhere in a fluid-pressure pipe-line would operate with beneficial results.

10 The essential operation of my invention will be understood from the description hereinbefore presented, and in this operation the closing of the main valve or plug 17 divides the pipe-line into what may be said to be two compartments, one being at one side of said plug and the other at the other side thereof, and permits the pressure to exhaust from one of said compartments against one of the auxiliary valves, in this instance 34, to uncover 15 a port and also to actuate the other auxiliary valve, to-wit, 37, so that it will open a duct from the other compartment, the pressure in which will act to close both auxiliary valves after the pressure in the first mentioned compartment has been relieved and becomes overbalanced by the pressure in the second mentioned compartment. The valves 20 34, 37 have a differential area, the area of the valve 34 being greater than the exposed area 30 of the valve 37, whose upper portion 38 enters the thimble 39, and hence the pressure in the hose-members may temporarily overbalance the pressure from the train pipe in the chamber 27, but when the pressure in the 35 hose-members has sufficiently exhausted the pressure from the train pipe, acting against the valve 37, will reseat both valves 34, 37 or move them to their closed position, the valve 37 then sealing the end of the train pipe.

40 I have hereinbefore described the operation of my angle-valve with respect to the full open and full closed positions of the plug 17. There may, however, be an intermediate operation which might be of special 45 benefit. I form the grooves 41, 43 in the plug 17 of such predetermined length that the exhaust from the hose-end of the valve will commence when the handle 22 has been turned, accidentally or otherwise, say about 50 seventeen degrees, and that the exhaust from the train end of said valve will commence when said handle has been moved toward its closed position about three additional degrees, under which condition there will be 55 an exhaust through the port 31, because during the first turning of the handle, say, seventeen degrees, the exhaust through the groove 41 lifted the valve 34 and caused it to elevate the valve 37. The handle 22 might 60 by accident or by being knocked by some chain or other part of the connections, be turned to a partly closed position, when the train is in motion and not intended to be stopped. The bleeding of the hose and 65 train-pipe under the accidental condition

stated would tend to apply the brakes, while at the same time the plug 17 would not be in its closed position, but only partly turned in that direction. One benefit of allowing the hose and train-pipe to bleed when the plug 70 17 is in a partly open position, is that the passage through the train-pipe system is then open and the engineer may under that condition utilize the entire train-pipe system in an emergency application of the brakes. It 75 is to be understood therefore that when I speak of the closed position of the plug 17 I do not mean in every instance that the plug is absolutely closed, because we obtain an operation when the plug is partly open, but 80 in the practical use of the valve the train-man will move the same either to its full open position or full closed position. The other operation to which I have just referred would arise more through accident than 85 otherwise, and should the handle 22 be turned by accident through a part of its throw only, the exhaust from both sides of the plug 17 would continue until the train-man discovered the cause of the difficulty 90 and righted the plug 17, turning said plug to its full open position or to a full closed position, as might be necessary.

I preferably allow the exhaust from the hose into the valve chamber 26 before the 95 train pressure can exhaust through the chamber 27, so that in the event that the valve 37 should by reason of frost or other cause cling to its seat, the movement of the valve stem 33 against said valve may detach the same 100 from its seat prior to the entrance of any pressure from the train-pipe tending to resist the action of said stem 33. The lower stem of the valve 37 and the upper end of the stem 33 may be in direct contact if desired, but I prefer to have said stems separated from each other a slight distance when the auxiliary valves are in their closed position, so that when the valve 34 starts upwardly to open the valve 37, the stem 33 may 110 strike the depending stem of the valve 37 with a sort of blow which would aid in detaching the valve 37 from its seat.

My angle-valve possesses many capacities for practical use and those that I have indicated are sufficient for the purposes of this application.

I do not limit my invention to details of form or construction further than the appended claims may require, because I regard 120 my invention as broadly new and of substantial benefit.

What I claim as my invention and desire to secure by Letters-Patent, is:

1. A valve of the character described comprising a casing to be interposed in a fluid pressure pipe-line and having a main valve member for opening and closing the main passage therethrough, auxiliary chambers having outlet ports, auxiliary valves with 125 130

in said chambers for controlling said ports, a duct leading from one side of said main valve when it is in closed position to one of said chambers and a duct leading 5 from the other side of said main valve, when closed, to the other of said chambers, the whole being so arranged that the pressure at one side of the main valve may exhaust into one of said chambers and move the valve 10 therein to open the exhaust port therefrom and effect the movement of the other auxiliary valve to its open position, whereby on the reduction of pressure at one side of said main valve, the pressure at the other side of 15 said valve may act to seat both of said auxiliary valves and close the ports from said chambers.

2. A valve of the character described comprising a casing to be interposed in a fluid pressure pipe-line and having a main valve member for opening and closing the main passage therethrough, auxiliary chambers having outlet ports, auxiliary valves within 20 said chambers for controlling said ports, a duct, leading from one side of said main valve when it is in closed position to one of said chambers and a duct leading from the other side of said main valve, when closed, to the other of said chambers, the whole being 25 so arranged that the pressure at one side of the main valve may exhaust into one of said chambers and move the valve therein to open the exhaust port therefrom and effect the movement of the other auxiliary valve 30 to its open position, whereby on the reduction of pressure at one side of said main valve, the pressure at the other side of said valve may act to seat both of said auxiliary valves and close the ports from said chambers, 35 said auxiliary valves having a differential exposed area to accelerate their closing action on the reduction of pressure at that side of the main valve first exhausting.

3. A valve of the character described comprising a casing to be interposed in a fluid pressure pipe-line and having a main valve member for opening and closing the main passage therethrough, auxiliary chambers having outlet ports, auxiliary valves within 40 said chambers for controlling said ports, a duct leading from one side of said main valve when it is in closed position to one of said chambers and a duct leading from the other side of said main valve, when closed, 45 to the other of said chambers, the whole being so arranged that the pressure at one side of the main valve may exhaust into one of said chambers and move the valve therein to open the exhaust port therefrom and effect 50 the movement of the other auxiliary valve to its open position, whereby on the reduction of pressure at one side of said main valve, the pressure at the other side of said valve may act to seat both of said auxiliary valves 55 and close the ports from said chambers, said 60

auxiliary valves having a differential area so that the pressure at that side of the main valve first exhausting may temporarily overcome the pressure from the other side of said main valve exhausting into the chamber 70 of its auxiliary valve.

4. A valve of the character described comprising a casing to be interposed in a fluid pressure pipe line and having a main valve member for opening and closing the main 75 passage therethrough, auxiliary chambers having outlet ports, auxiliary valves within said chambers for controlling said ports, a duct leading from one side of said main valve when it is in closed position to one of 80 said chambers and a duct leading from the other side of said main valve, when closed, to the other of said chambers, said ducts being partly formed in said casing and partly in said main valve member and being closed 85 when said main valve member is in its open position.

5. A valve of the character described comprising a casing to be interposed in a fluid pressure pipe line and having a rotary plug 90 for opening and closing the main passage therethrough, auxiliary chambers having outlet ports, auxiliary valves in said chambers for controlling said ports, a duct leading from said main passage at one side of 95 said valve, when the valve is in closed position, to one of said chambers and a duct leading from said main passage at the other side of said plug, when the plug is in closed position, to the other of said chambers, said 100 ducts in the open position of said plug being closed, and the pressure at one side of said main passage being free to close its auxiliary valve on the reduction of pressure at the other side of said passage.

6. In a compressed air system for railway trains, in combination, train-pipes for each car, hose members for coupling said pipes between adjacent cars and valves of the character described on the ends of said pipes and receiving said hose members, said valves each comprising a main casing, a plug therein for opening and closing the main passage therethrough, means on the closing of said plug for bleeding or venting the hose, means, 110 also on the closing of said plug, for permitting the air in the train pipe to exhaust to some extent, said last mentioned means being adapted to be closed by the pressure in the train pipe when the pressure in the hose 115 has exhausted.

7. In a compressed air system for railway trains, in combination, train-pipes for each car, hose members for coupling said pipes between adjacent cars and valves of 120 the character described on the ends of said pipes and receiving said hose members, said valves each comprising a main casing, a plug therein for opening and closing the main passage therethrough, auxiliary chambers 125

65 and close the ports from said chambers, said 130

- having outlet ports, auxiliary valves within said chambers for controlling said ports, a duct leading from the hose side of said plug when it is in closed position to one of said 5 chambers and a duct leading from the other side of said plug, also when in closed position, to the other of said chambers, said auxiliary valves being in coöperative relation, whereby when the said plug is moved 10 to closed position, the pressure in the hose may exhaust into one of said auxiliary chambers and open both auxiliary valves and whereby the pressure in the train pipe may exhaust sufficiently to apply the brakes and 15 finally on the reduction of pressure in the hose close both said auxiliary valves, leaving the train-pipes closed at their adjoining ends.
8. In a compressed air system for railway 20 trains, a valve of the character described comprising a casing to be interposed in the pipe-line of said system and having a main valve-member for opening and closing the main passage therethrough, means on the 25 closing of said main valve member for permitting the exhaust of the air pressure at one side thereof and means, also on the closing of said main valve member, for permitting the exhaust to some extent at the other 30 side of said member, said last mentioned means being adapted to be closed by the pressure on said side of said valve member when the pressure at the other side of said member has exhausted.
- 35 9. In a compressed air system for railway trains, a valve of the character described comprising a casing to be interposed in the pipe line of said system and having a rotary plug with a handle thereon for opening and closing the main passage 40 through said casing, means on the closing of said plug for permitting the exhaust of the air pressure at both sides thereof, said means being adapted to be closed by the 45 pressure in said system at one side of said valve when the pressure on the other side of said valve has exhausted.
10. In a compressed air system for railway 50 trains, in combination, train-pipes for each car, hose members for coupling said pipes between adjacent cars and valves of the character described on the ends of said pipes and receiving said hose members, each of said valves comprising a main casing, a plug 55 therein for opening and closing the main passage therethrough, and means, on the closing of said plug, for permitting the pressure to exhaust from both sides of said plug, thereby exhausting the hose and applying 60 the brakes, said means being adapted on the exhaust of the hose to be closed by the pressure in the train-pipes.
11. In a compressed air system for railway 65 trains, in combination, train-pipes for each car, hose members for coupling said pipes
- between adjacent cars and valves of the character described on the ends of said pipes and receiving said hose members, said valves each comprising a main casing, a plug therein for opening and closing the main passage therethrough, auxiliary chambers having outlet ports, auxiliary valves in said chambers for controlling said ports, a duct leading from the hose side of said main valve to one of said chambers, and a duct leading from the 70 train side of said main valve to the other of said chambers, said ducts being closed by said plug when the same is in its open position and opened by said plug when it is moved to its closed position, and the valve in 75 the auxiliary chamber for the hose connections being of piston type and having a stem engaging the auxiliary valve in the auxiliary chamber for the train-side of the main valve, and said last mentioned auxiliary valve being 80 of disk type and having an upper cylindrical member guiding in a closed thimble constituting a portion of the main casing, whereby the pressure in the hose when the main plug is turned to closed position may open both 85 auxiliary valves and exhaust, and whereby the pressure in the train pipe may exhaust sufficiently to apply the brakes and then act to move said auxiliary valves to their closed 90 position.
- 95 12. A valve of the character described comprising a casing to be interposed in a fluid pressure pipe line and having a main valve member for opening and closing the main passage therethrough, auxiliary chambers 100 having outlet ports, auxiliary valves within said chambers for controlling said ports, a duct leading from one side of said main valve when it is in closed position to one of said chambers and a duct leading from the other side of said main valve, when closed, to the other of said chambers, said ducts being partly formed in said casing and partly in said main valve member and being closed 105 when said main valve member is in its open 110 position, and said ducts also being so proportioned and located that they become partly opened to exhaust during the closing movement of the main valve member and before said member closes the passage through the 115 pipe line.
13. A valve of the character described comprising a casing to be interposed in a fluid pressure pipe line and having a rotary plug 120 for opening and closing the main passage therethrough, auxiliary chambers having outlet ports, auxiliary valves in said chambers for controlling said ports, a duct leading from said main passage at one side of said valve, when the valve is in closed position, to one of said chambers and a duct leading from said main passage at the other side of said plug, when the plug is in closed position, to the other of said chambers, said ducts in 125 the open position of said plug being closed, 130

and the pressure at one side of said main passage being free to close its auxiliary valve on the reduction of pressure at the other side of said passage, and said ducts also being so proportioned and located that they become partly opened to exhaust during the closing movement of said plug and before said plug has closed the passage through the pipe line.

Signed at New York city, in the county of New York and State of New York, this 16th 10 day of March, A. D. 1918.

JAMES N. WEIKLY.
